UNITED STATES PATENT OFFICE.

ALEXIS R. PRIBIL, OF DETROIT, MICHIGAN, ASSIGNOR TO GEORGE W. BOWEN, OF AUBURN, NEW YORK.

GREASE-CUP.

1,150,146.

Specification of Letters Patent. Patented Aug. 17, 1915.

Application filed August 25, 1913. Serial No. 736,420.

To all whom it may concern:

Be it known that I, ALEXIS R. PRIBIL, a citizen of the United States, and a resident of Detroit, in the county of Wayne and 5 State of Michigan, have invented a new and useful Grease-Cup, of which the following is a specification.

This invention relates to grease cups including two main elements connected by 10 screw threads, and has for its object a particularly simple and efficient cap for normally holding the main elements from relative movement, and for also excluding dust from the interior of the grease cup; and the 15 invention consists in the novel features of construction hereinafter set forth and claimed.

In describing this invention reference is had to the accompanying drawings in which 20 like characters designate corresponding parts in all the views.

Figures 1 and 2 are, respectively, an elevation and a vertical sectional view of one 25 form of this grease cup. Fig. 3 is a plan view of the base of my grease cup. Fig. 4 is an inverted plan view of the piston and the cap. Fig. 5 is an enlarged cross-sectional view, parts being omitted, illustrating the locking operation of the cap.

30 1 is the base element of my grease cup, the same including the internally threaded barrel portion 2 and a depending stem 3 for attachment to the part to be lubricated, the stem having an outlet passage 4.

35 5 is the piston element which includes a head threading into the barrel 2 and an axial stem 6 provided with a handle 7 at its upper end.

40 8 is the cap, which is in the form of an inverted cup, is composed of thin resilient material and has the central portion of its closed end fixed to the stem 6. Said stem preferably extends through a central opening in the closed end of the cap and is provided with a shoulder 9 engaging the inner 45 face of the closed end of the cap, and a removable shoulder 10 opposed to the shoulder 9 and engaging the outer face of said closed end, these shoulders 9 and 10 being of less diameter than the closed end of the cap.

50 The shoulder 10 is held in position by the handle 7 which is secured to the upper end of the stem 6 in any suitable manner, as by a pin 11. The outer portion of the closed 55 end of the cap 8 and the side wall of said

cap are resilient and free to yield or distort, and said side wall incloses and substantially fits the barrel portion 2.

In the illustrated embodiment of my invention, the barrel portion 2 is formed with 60 a plurality of lengthwise peripheral grooves 12 spaced equidistantly apart, and the side wall of the cap 8 is formed with a different number of inward projections or shoulders 13 for entering the grooves 12, the projections 13 being also spaced equidistantly, so that but one is located in a groove at a time while the others press on the periphery of the barrel portion 2 and slightly distort and tension the resilient side wall of the cap 8 70 to hold one of the said projections in the groove, (Fig. 5) the grooves and projections being so shaped that the projections or shoulders readily ratchet into and out of the grooves. 75

In the illustrated form of the invention, there are four equidistantly spaced grooves 12 and three equidistantly spaced projections 13 so that one groove and one projection engage upon but slight turning of the 80 piston 5. The projections 13 are preferably formed by pressing portions of the cap 8 inwardly.

The cap 8 is practically dust proof as said 85 cap 8 and barrel portion 2 are so proportioned that when one of the projections 13 is in one of the grooves 12, the greater portion of the side wall of the cap is held tightly against the periphery of the barrel portion 2, and remaining portions of the opposing surfaces of said parts 2 and 8 are 90 but slightly separated.

What I claim is:

1. A grease cup comprising two elements, one having an internally threaded barrel 95 and the other including a head threading in the barrel and a cap carried by the element including the head, said cap being fixed relatively to the head and comprising a resilient continuous side wall telescoping on the barrel, said cap and barrel having interlocking surfaces, and additional surfaces coöperating for distorting the side wall of the cap as a whole for holding the interlocking surfaces in engagement. 100

2. A grease cup comprising two elements, one having an internally threaded barrel and the other including a head threading in the barrel, and a cap carried by the element including the head, and fixed relatively to 110

the head and comprising a resilient continuous side wall inclosing and engaging the barrel, one of said engaging parts having a lengthwise groove, and the other of said engaging parts having projections for entering the groove, the projections being spaced apart so that when one enters the groove another presses against the opposing surface of the part formed with the groove and distorts and tensions said side wall to hold said one of the projections in the groove, substantially as and for the purpose specified.

3. A grease cup comprising two elements, one having an internally threaded barrel and the other including a head threading in the barrel, and a cap carried by the element including the head, and fixed relatively to the head and comprising a resilient continuous side wall inclosing and engaging the barrel, one of said engaging parts having a plurality of lengthwise grooves spaced equidistantly apart, and the other of said engaging parts having a different number of equidistant projections for entering the grooves, whereby when one projection enters a groove the remaining projections press against the opposing surface of the part formed with the grooves, and distort and tension said side wall to hold said one of the projections in the groove, substantially as and for the purpose set forth.

4. A grease cup comprising a base having an internally threaded barrel portion, a piston member including a head and a stem, the head threading into the barrel, and an inverted cup-shaped cap having its closed end fixed to the stem and its side wall resilient and continuous and encircling the barrel portion of the base, said barrel portion and said wall having interengaging means, a part of which are designed to interfit, and another part to coöperate for distorting the side wall of the cap and holding the interfitting parts in engagement.

5. A grease cup comprising a base having an internally threaded barrel portion, a piston element including a head and a stem, the head threading into the barrel portion, and a cup-shaped cap having its closed end fixed to the stem and its side wall resilient, the side wall being continuous and encircling the barrel portion of the base, said barrel portion having a plurality of lengthwise peripheral grooves equidistantly spaced, and said side wall having a different number of internally equidistant projections, whereby when one projection enters a groove the other projections press against the periphery of the barrel portion and dis-

tort the cap, substantially as and for the purpose specified.

6. A grease cup comprising a base having an internally threaded barrel portion, a piston element including a head and a stem, the head threading into the barrel portion, and a cup shaped cap having its closed end provided with a central opening through which the stem extends, the barrel portion of the cap inclosing and engaging the periphery of the barrel portion of the base, the stem being formed with a fixed shoulder engaging the inner side of the closed end of the cap and with a removable shoulder engaging the outer side of the closed end of the cap, said shoulders being of less diameter than said closed end, and a handle mounted on the stem above the removable shoulder, substantially as and for the purpose set forth.

7. A grease cup comprising a base having an internally threaded barrel portion, a piston element including a head and a stem, the head threading into the barrel portion, a cup shaped cap having its closed end fixed to the stem, and the outer portion of the closed end and its side wall being resilient, the side wall being continuous and encircling the barrel portion of the base, said barrel portion having a plurality of lengthwise peripheral grooves equidistantly spaced, and said side wall having a different number of internally equidistant projections whereby when one projection enters a groove the other projections press against the periphery of the barrel portion and distort the cap as a whole, substantially as and for the purpose described.

8. A grease cup comprising a base having an internally threaded barrel portion and a plurality of lengthwise peripheral grooves spaced from one another, a head threading into the barrel portion, and an inverted cup-shaped cap associated with the head and having a continuous resilient side wall encircling the barrel portion, said cap being provided with a plurality of internal projections dissimilarly spaced from the grooves on the barrel, substantially as described.

In testimony whereof, I have hereunto signed my name in the presence of two attesting witnesses, at Detroit, in the county of Wayne, in the State of Michigan, this 15th day of August, 1913.

ALEXIS R. PRIBIL.
